UNITED STATES PATENT OFFICE

2,119,014

AUTOMATIC STOP FOR A THREADING DIE
HEADHarry T. Kimlin and Douglas O. Kimlin,
Hyde Park, N. Y.

Application September 17, 1936, Serial No. 101,260

3 Claims. (Cl. 10—124)

This invention relates primarily to a portable power or hand driven machine for threading pipe, in which a standard type of ratchet die-head is employed, as shown in U. S. Patent No. 1,966,124; and more particularly to a die-head of the self-feeding type, where the cutting die is fed to the pipe in a positive manner.

In die-heads of this kind, the body is rigidly clamped upon the pipe which is also rigidly held in a pipe vice, and the die-head in which the cutting dies are mounted is threaded into the body of the tool in such a manner that as the die-head is rotated by the action of a handle operated ratchet, the die-head will travel inwardly within the body causing the cutters to have a positive "lead" and not depending upon the thread that is being cut to force the dies or cutters upon the pipe.

The objection to this automatic feed is that it does not have any stop or throw-off when the required number of threads have been cut on the pipe, and when such a die-head is employed in the power operated machine as described in U. S. Patent No. 1,966,124, if the operator is not present to stop the machine or to change the ratchet feed to neutral, the die-head will become jammed in the body and the threads may become damaged as well as the cutters.

To overcome these and other objections and to provide a die-head that shall have an automatic feed together with a stop to render the feed inoperative when the proper length of thread has been cut, we have devised a novel die-head or attachment for the usual types now in use.

The object of the invention is to provide a die-head of the self-feeding type having automatic means for stopping the self-feeding means when the desired number of threads have been cut.

Another object of the invention is to provide a stop for a self-feeding die-head that may be incorporated into the device or be in the form of an attachment thereto.

Another object of the invention is to provide a die-stock of this kind that may be operated by hand as well as in a power driven machine.

With these and other objects in view, our invention consists in certain novel construction and combination of parts as will hereinafter be fully described and claimed and further illustrated in the accompanying drawing which forms a part hereof and in which like figures of reference refer to corresponding parts in all of the views, and it is understood that slight changes may be made without departing from the spirit of the invention.

In the drawing:

Figure 1 is a top plan view of a standard type of ratchet operated die-stock in which our device has been incorporated.

Figure 2 is a vertical sectional view of the same, showing a pipe being threaded, and the stop device in operation.

Referring to the drawing:

To fully understand the operation and advantages of the device, it will be necessary to describe the construction and operation of the usual type of die-stock, which we have illustrated and which comprises:

A tubular body portion 10 formed with the flange 11 within which are adjustably mounted the pipe clamps 12 for rigidly securing the body 10 to the pipe 13, which, of course, is also rigidly secured in the usual pipe vice (not shown in the drawing); the pipe clamps or shoes 12 are mounted on the inner ends of the guide rods 14 which are slidably mounted in the walls of the flange 11, and the shoes 12 are operated by the thumb bolts 15 which are threaded through the walls of the flange 11 and are rotatable within a plate 16 secured to the ends of the rods 14 by a screw 17, so that by the rotation of these bolts 15 the shoes 12 are clamped on the pipe 13.

The upper end of the body portion 10 is formed with an internal threaded portion 18 for the external threaded portion 19 of a tubular flanged member 20 having the internal threaded portion 21.

Between the upper end of the body member 10 and this flanged member 20 is freely rotatably mounted the ratchet ring member 22 which is provided with the handle socket 23 for the handle 24 and the ratchet boss 24.

This ring or operating member 22 has a central opening 25 embracing the flanged member 20 which is flanged as at 26 and rotatably mounted within this flange 26 is a ring 27 formed on its periphery with ratchet teeth 28 and adapted to be engaged by a ratchet 29 for operation in either direction according to the way the ratchet 29 is set by the finger knob 30 by pulling it out against the action of the spring 31 to turn it; accidental turning being prevented by a transverse pin 32 adapted to engage the slot 33 in the boss 24; this ratchet ring 27 is held in the member 22 by the flanged member 20 and a retaining ring 34 secured in the operating member 22 by the screws 35.

The cutter head 36 has an axial bore 37 for the passage of the pipe 13 and a depending externally threaded body 38 threaded into the bore 39.

21 of the flanged member 20 to constitute the feed.

The upper face of this cutter head 36 is formed with the usual holders 39 within which are adjustably mounted in the usual manner, the cutters 40.

To prevent rotation between the ratchet ring 27 and the cutter head 36, a set of posts 41 are provided which have their inner ends rigidly secured to the ratchet ring 27 and which extend through bearings 42 formed in the cutter head 36 allowing the head 36 to freely slide on said posts 41.

As the ratchet ring 27 is rotated by the handle 44, the cutter head 36 will be rotated on the pipe 13 to cut the threads 45 and at the same time the threaded portion 38 engaging the threaded portion 21 of the member 20, will act as an automatic feed for the cutter head 36 on the pipe 13, but should it be permitted to enter too far into the member 20, it will become jammed.

To prevent this and provide an automatic stop for the feed we have provided the handle socket 23 with a boss 46 within which is threaded a stop bolt 47 the height of which may be varied and locked by the nut 48.

To the face of the cutter head 36 is secured a stop arm 49 by the screws 50, or this arm may be integral with the head.

30 When the operation of threading the pipe 13 is started the cutter head 36 is backed out of the flanged member 20 to its full extent, and as the feeding action takes place, the arm 49 will freely pass the stop pin 47, but when the required 35 depth of thread is attained, the arm 49 will contact with the pin 47 and prevent further inward movement of the cutter head 36 and thus any further feed.

40 The next backward or oscillating movement of the ring 22 by the handle 44 will back the cutters on the threads already cut so that any further oscillation of the die-head will only oscillate the cutters on the already cut threads and will not continue the cutting operation.

Having thus described our invention, what we claim is new and desire to secure by Letters Patent, is:

1. An automatic and adjustable feed stop for ratchet operated threading die-stocks of the class 5 described, comprising in combination with a die-stock having a body member for attachment to a pipe, a cutter-head threaded therein to form a feed and ratchet means for rotating the cutter-head, of an arm carried by the cutter head and 10 an adjustable stud carried by the ratchet means adapted to contact with said arm when a predetermined length of thread has been cut to prevent further rotation between the cutter-head and the ratchet means. 15

2. An automatic stop for the feeding means of a ratchet operated thread cutting machine having a non-rotating body, a die-head threaded therein to provide a feed, and a ratchet operated means for rotating the die-head upon the pipe 20 and with respect to the body, of means for limiting the travel of said feeding means, comprising an adjustable stop mounted upon the die-head 25 rotating means and an arm secured to and projecting from said die-head and adapted to contact with said stop when the feeding means has completed a predetermined length of travel.

3. In a thread cutting die-head having a ratchet handle and in combination with a non-rotating 30 body member having a die-head threaded therein capable of in and out rotary travel with respect to the body member to provide a feed, of a stop adjustably mounted on said ratchet handle and an arm secured to said die-head and adapted to 35 contact with, and stop the inward travel of the die-head with respect to the body member when a predetermined length of travel of the die-head has been reached due to its in and out rotary travel. 40
